U.S. PATENT DOCUMENTS

4,706,431 A * 11/1987 Corvese 52/716.1

FIG. 1 is a perspective view of an extrusion or similar article showing my new design;

FIG. 2 is an end view thereof;

FIG. 3 is a front view thereof;

FIG. 4 is a rear view thereof;

FIG. 5 is a top view thereof; and,

FIG. 6 is a bottom view thereof.

It is a feature of the extrusion of my new design that it can accommodate and retain, to extend along a lineal expanse thereof, an insertable strip or band which may carry selectable decorative indicia.
